UNITED STATES PATENT OFFICE.

WALTER E. HOSCH, OF ST. LOUIS, MISSOURI.

RIBBON MEASURING, COST-COMPUTING, AND WINDING MACHINE.

1,242,192.

Specification of Letters Patent.

Patented Oct. 9, 1917.

Application filed February 8, 1915. Serial No. 6,671.

To all whom it may concern:

Be it known that I, WALTER ESTES HOSCH, a citizen of the United States, residing in the city of St. Louis and State of Missouri, 5 have invented new and useful Improvements in Ribbon Measuring, Cost-Computing, and Winding Machines, of which the following is a specification.

This invention relates to measuring machines, and has for its general object to provide a machine for measuring various desired lengths of ribbons, laces, and similar materials relatively narrow in width, for indicating the cost of the amount of material measured, for severing the material at the termination of the measured portion, and for indicating the linear measurement of pieces of ribbon or the like of unknown length passed through the machine.

10 The machine has for specific objects to provide a receptacle for accommodating the bolt of ribbon, or other material, which is to be measured, or from which a measured portion is to be severed; to provide a novel construction of winding-drum which will automatically compensate for the increasing speed of movement of the material wound upon it, as compared with the speed of movement of the feed-roll, which latter bears 15 a fixed relation to the normal speed of movement of the winding-drum; to provide a winding-drum which will permit the material wound thereon to be readily removed therefrom; to provide a novel arrangement 20 of cutter for severing the material at the termination of the measured portion; to provide novel means for setting and releasing a friction or pressure roll with reference to the feed-roll of the measuring machine; to 25 provide novel measuring and cost-computing mechanism; and to provide means for releasing a spring-controlled computing-drum at the end of the measuring operation to permit its spring to return it to zero.

30 In addition to the above general and specific objects of the invention other objects of the invention are concerned with novel details of construction and combinations and coördinations of parts which can be more 35 clearly understood from the detail description following.

The machine forming the subject-matter of this invention is particularly adapted for measuring ribbons of various widths, and 40 the material measured will, for the sake of 45 brevity of description, be referred to as

ribbon. I wish it understood, however, that by the use of the term "ribbon" in the specification and claims I do not thereby intend to limit the application of the machine to the 50 measurement of ribbons only, as the machine may be used for measuring laces and other material of relatively narrow width, as above indicated.

In the accompanying drawings,—

Figure 1 is a top plan view of the machine constructed according to my invention;

Fig. 2 is a view in front elevation;

Fig. 3 is a view in rear elevation;

Fig. 4 is a transverse sectional view on the line 4—4 of Fig. 1, and viewed in the direction of the arrows;

Fig. 5 is a section on the line 5—5 of Fig. 1, and viewed in the direction of the arrows;

Fig. 6 is a section on the line 6—6 of Fig. 5, and viewed in the direction of the arrow;

Fig. 7 is a view of the right-hand side of 80 the machine, the casing being broken away to show the shear for severing the ribbon;

Fig. 8 is also a view of the right-hand side of the machine, but showing the winding drum and parts connected therewith in 85 section;

Fig. 9 is a fragmentary sectional view of a portion of the front of the machine showing the computing-drum in section, and the restoring spring and stop mechanism therefor;

Fig. 10 is a fragmentary sectional view showing the actuating mechanism for the computing-drum, and also showing the restoring spring and stop mechanism for the 95 winding-drum, the line of section being substantially on the line 10—10 of Fig. 9;

Fig. 11 is a fragmentary sectional view taken approximately on the same line of section as Fig. 6, but looking in the direction 100 opposite to that indicated by the arrows in Fig. 5, the view showing the mechanism for operating the friction roller to release and lower the same, and for releasing the driving mechanism from the computing-drum;

Fig. 12 is a section on the line 12—12 of Fig. 11, and viewed in the direction of the arrow; and

Fig. 13 is a detached sectional view showing the manner of fastening the material to be measured on the winding-drum.

Referring now to these drawings, the num-

meral 1 indicates the casing or frame of the machine, which comprises a longitudinally-extending portion 2, and a housing 3 extending transversely of the machine at the front thereof. The portion 2 of the frame extends rearwardly from the housing 3 and provides two recesses 4, 5, respectively, at opposite sides of the machine, the recess 4 affording a holder for the bolt of ribbon to be measured, or a portion of which is to be measured, and the recess 5 accommodating a winding-drum 6 to be later described. The numeral 7 (Fig. 4) indicates a feed roll, and the numeral 8 a friction roll adapted to coöperate therewith. The roller 7 is mounted at its ends in brackets 9 supported on a base-plate 10 mounted in and extending longitudinally of the central portion 2^a of the part 2 of the frame. Mounted at its front end portion upon the housing 3 is a superstructure 11 (see Figs. 7 and 8) forming a housing, the bottom of said superstructure beyond the rear side of the housing 3 being spaced a slight distance from the top of the central portion 2^a of the casing, providing a space 12 for the insertion of the material to be measured, as will presently appear. Referring to Fig. 5, there are mounted in opposite ends of the superstructure 11 journal plates 13, 14, the plate 14, or that at the front of said superstructure, extending downward through the housing 3 and being connected to the base-plate 10 before referred to. Journaled at opposite ends in the plates 13 and 14 is a worm-shaft 15 which is provided at one end with a pinion 16 which is in mesh with a gear-wheel 17. The gear-wheel 17 is fast on a stub-shaft 18 journaled in the plate 14, and extending through the front plate 19 of the machine, and being there provided with a squared end on which is secured a handle 20 by means of a screw 21. Secured on the plate 14 is a stud 22 on which is loosely mounted a pinion 23 and a gear-wheel 24 connected to the pinion, said pinion and gear being held on the stud 22 by means of a screw 25. The pinion 23 is in mesh with the gear 17, and the gear 24 is in mesh with a pinion 26 which is fast on a shaft 27 on which the roller 7 is mounted in the brackets 9. The pinion 26 in turn is in mesh with a gear 28 which is mounted on a stud 29 secured in the plate 14, and the gear 28 in turn meshes with a pinion 30 which is fast on a worm-shaft 31 journaled in brackets 32 on the under side of the plate 10. The worm 33 of said worm-shaft is in mesh with a worm-gear 34 which is journaled on a stub-shaft 35 mounted in a bracket 36 (Fig. 11) secured to the under side of the plate 10. Pivottally mounted on the stub-shaft 35 and located on opposite sides of the gear 34 are two plates 37 which constitute a frame in which is supported on a journal 38 a gear-

wheel 39 which meshes with a relatively large gear-wheel 40 mounted centrally of a shaft 41 on which are mounted two cylindrical members constituting a computing-drum 42. The shaft 41 extends between and is journaled at opposite ends in two brackets 42^a (Figs. 8 and 9) projecting forwardly from opposite ends of the housing 3. The two parts of the computing-drum are the same, and the separation is only to provide space for the gear 40 (Fig. 4). The space between the opposing ends of the computing-drum is the same as the space between two of its sub-divisions, as hereinafter referred to, so that such space does not interrupt the continuity of the markings of said drum. The plates 37 are connected and constitute a bracket supporting the gear 39, and as said plates are pivotally mounted on the shaft 35 said gear can be turned into and out of contact with the gear 40. Normally, engagement of said gears is maintained by means of a leaf-spring 43 mounted on the under side of the plate 10 and having its free end bearing against the connected arms 37. Referring to Figs. 9 and 10, there is secured to one end of the shaft 41 the end of a coil spring 44, the other end of which is secured in a housing 45 mounted on one of the brackets 42^a. Projecting upward from this housing is an arm 46. On a corresponding end of the computing-drum 42 is a stop 47 which normally engages the arm 46. On turning the crank-handle 20 the computing-drum will be turned, through the various pinions and gears described, against the resistance of its spring 44, which will be thereupon coiled; the stop 47 during this movement moving away from the arm 46. Mechanism, to be later described, is provided for moving the gear 39 out of mesh with the gear 40, and when this occurs the spring 44 turns the computing-drum in the reverse direction until its movement is stopped at the zero position by engagement of the stop 47 with the arm 46. The turning of the crank-handle 20 also, through the medium of the pinion 26, rotates the feed roll 7. In order to provide for drawing the material to be measured over the roll 7 I provide the friction roll 8 which is mounted and operated in the manner now to be described. The numeral 48 (Figs. 4 and 11) indicates a yoke-frame which is pivotally mounted at its ends on a rod 49 secured in brackets 50 mounted on a supporting-plate 51 within the superstructure 11. The friction roller 8 before referred to is journaled at its opposite ends in the yoke 48. A spring 52 bearing on the yoke 48 tends normally to force the roller 8 upon the roller 7. Centrally of the yoke 48 is located a stud 53 (Figs. 11 and 12) which engages in a slot 54 formed in the end of a lever 55 which is pivotally mounted at 56 on a plate 57 lying

opposite to the plate 51, said plates extending downward in parallel relation from the upper part of the superstructure 11 to the plate 10 to which they are secured, and being provided with slots 58 in alignment with the slots 12 (Fig. 4) of the superstructure 11. The opposite end of the lever 55 engages in a slot in the upper end of a rod 59 (Figs. 5 and 12), which is slidably mounted 10 in its lower portion in a boss 60 provided on the plate 57. The rod 59 is provided near its upper end with a collar 61, and surrounding said rod and extending between said collar and the top of the boss 60 is a coil 15 spring 62. The numeral 63 (Fig. 11) indicates a rod similar to the rod 59, the rods 59 and 63 being secured at their lower ends in a bridge-piece 64, and being held by said bridge-piece in parallel relation. The rod 20 63 is provided at its upper end with a push-button 65. Projecting at right angles from one of the plates 37 is a pin 66. Secured to the bridge-piece 64 is a downwardly-projecting arm 67 having a cam surface 68 (Fig. 4) which is adapted to engage the pin 66. With the parts arranged as described, if the push-button 65 is depressed the rod 25 59 will rock the lever 55 to raise the yoke 48 and thereby lift the roller 8 from engagement with the roller 7, or with the goods between said rollers; and at the same time the cam surface 68 on the arm 67, engaging the pin 66, will rock the bracket arms 37 outward, thereby moving the gear 35 39 out of mesh with the gear 40, and permitting the computing-drum 42 to be returned to zero position by its spring 44. As the rods 63 and 59 are pressed downward against the resistance of the spring 62, it is 40 necessary to provide means for holding the rods in this position to maintain the roller 8 out of contact with the roller 7 while the ribbon is being inserted between said rollers. To this end, I mount in the top of the housing 3 a push-button 69, the stem of which has secured on its lower end a disk 70 (Fig. 4), which engages the upper end of one member 71 of a bell-crank lever pivoted at 45 72 on a bracket 73 secured on the inner side 50 of the front wall of the casing. Slidably mounted in this bracket is a bolt 74 normally pressed inward by a leaf-spring 75, and which bolt is provided with a recess which is engaged by the free end of the other 55 member 76 of said bell-crank lever. The rod 63 is provided intermediate its ends with a notch 77, and the end of the bolt 74 normally engages the said rod. When the rod 63 is depressed the notch 77 will be brought 60 opposite the end of the bolt 74 which springs into engagement with said notch and thereby prevents the said rod from rising. In this way the roller 8 is held in an elevated position. When it is desired to lower the 65 roller 8 into contact with the ribbon, so that the latter may be drawn through the machine by rotating the roller 7, the push-button 69 is depressed, whereby the engagement of the disk 70 with the arm 71 of the bell-crank lever will cause the other arm 76 of said lever to withdraw the bolt 74 from engagement with the notch 77, whereupon the spring 62 will at once throw the rod 59 upward and the inner end of the lever 55 downward, thereby lowering the yoke 48 with the roller 8, the latter being held in yielding but firm engagement with the ribbon so that the latter will be drawn between the rollers as the roller 7 is rotated. Pivotally mounted on an off-set 77^a (Fig. 7) 75 on the plate 51 is a shear or cutter 78, the same being pivoted below the alining recesses 12 and 58, as indicated at 79. The shear 78 is provided with a slot 80 in which is slidably engaged one end of a spring arm 81, the other end being fastened in the journal-plate 14. Secured on the outer end of the shear is a thumb-piece 82, the stem 83 of which extends through and works in a slot 84 (Fig. 8) provided in the wall of the 80 superstructure 11. By pressing down on the thumb-piece 82 the shear 78 will be depressed. Coöperating with the shear 78 is a blade 85 (Fig. 7) which is fixedly secured to the plate 51 to extend parallel with the 85 bottom of the recess 58 therein. The numeral 86 indicates generally a winding-drum (see Figs. 1 and 8), supported at its inner end on a circular head 87, having a hub 88 which projects from 90 opposite sides of the disk, and loosely mounted on a shaft 89 provided with a collar 90, against which the inner end of the hub 88 frictionally engages. The outer end of the shaft 89 is screw-threaded as shown, 100 and mounted on this screw-threaded end is a nut 91. Surrounding the portion of the hub 88 projecting rearwardly from the head 87 is a coil spring 92, which extends between the rear face of the head 87 and a disk 105 93, loosely mounted on the hub 88 and engaged by the nut 91. The shaft 89 is a stub-shaft, and is journaled in and extends between the front and rear walls of the housing 3. Mounted on this shaft, (see Fig. 6) 110 is a pinion 94 which is in mesh with a gear-wheel 95 mounted on a stud 96, the gear-wheel 95 being in mesh with a similar gear-wheel 97 mounted on a stud 98, and the gear-wheel 97 being in mesh with the gear 28, 115 before referred to. The studs 96 and 98 are mounted in the outer or front wall of the housing 3. It will thus be seen that as the crank-handle 20 is turned the various gears and pinions described will cause the shaft 120 89 and the winding-drum 86 to be rotated. Beyond the head 87 the said winding-drum, which is cylindrical in form, comprises a series of spring-tongues 99, between which are longitudinally-extending recesses 100. 130

These recesses provide a ready means for securing the end of the ribbon to be measured to the winding-drum, as will readily be apparent from Fig. 13, it being only necessary to insert the ribbon under one of the tongues 99 and therefore into two of the recesses 100, and when the drum is rotated the ribbon will be held sufficiently secure to be wound upon the drum.

- 10 It will be observed that the winding-drum is only frictionally mounted upon the shaft 89, and the purpose of this is to permit the winding-drum to slip on said shaft to compensate for the increase in diameter of the body of ribbon wound upon it. The frictional engagement of the winding-drum with the shaft is secured by contact of the inner end of the hub 88 with the collar 90 on said shaft, and said hub is caused to bear 20 with greater or less force upon the collar 90 by turning the nut 91 in one direction or the other, the screwing up of said nut forcing the disk 93 into engagement with the spring, which in turn presses the hub against the collar with greater force, and the unscrewing of the nut permitting the spring to force the disk 93 outward and thereby decrease the pressure tension of the spring upon the head 87.
- 30 An important feature of the invention is the construction of the winding-drum which, by reason of the spring-tongues, permits the ribbon wound thereon to be readily removed; such operation only requiring the operator to press his hand about the ribbon and slightly squeeze it in order to press the tongues 99 together, which thereby decreases the diameter of the winding-drum and permits the ribbon to be easily slid therefrom.
- 40 Secured at opposite ends on and surrounding the brackets 42^a is a curved housing 101 (Fig. 10), which is substantially concentric with the computing-drum 42, and lies at a slight distance from the periphery thereof.
- 45 The housing 101 is provided in its upper side with a longitudinally-extending opening over which extends a magnifying glass 102 (Fig. 5) which is held in place by a frame 103 secured on said housing 101. The
- 50 frame 103 is provided with sight openings 104 which expose the magnifying glass to view, the openings 104 being separated at the center of the frame by an integral web 105 which serves to cover the spacing between
- 55 the two members of the computing-drum, and to hide said space and the gear-wheel 40 from view. Extending along the upper edge of the sight openings 104 is a series of numbers 106 (Fig. 1) indicating various prices per yard. The computing-drum 42 is provided at opposite ends with a series of corresponding figures and fractions 107, indicating yards and fractions of yards, the figures and fractions running in order, after
- 60 "0"; from "1" up to "9 $\frac{1}{2}$ ". Running longi-

tudinally of the computing-drum after each number of the series 107 is a series of numbers 108 indicating the cost of the amount of ribbon indicated by any one of the numbers in the series 107 at the price per yard indicated by any one of the series of numbers 106. The series of numbers 108 after each of the numbers of the series 107 are arranged in order in line with the corresponding numbers 106, so that when the computing-drum is turned to indicate that a given number of yards of ribbon have been measured, the total cost at the price per yard at which the ribbon was sold will appear immediately below or opposite the price number in the series of figures 106. Mounted at opposite ends in the ends of the superstructure 11 (Fig. 4) to one side of the worm-shaft 15 is a rod 109 on which is slidably mounted a block 110 provided with a pointer 111 and a handle 112 projecting through one side of the superstructure 11 and working in a slot 113 (Fig. 6) therein. Supported at opposite ends on the top of the plates 13 and 14 is a scale-plate 114 having division marks thereon indicating yards and fractions of yards, a row of figures 115 indicating yards and running from "0" to "10", and a second row of figures 116 indicating yards and running in the reverse direction from "0" to "10". The row of figures 116 are preferably of a different color from the row of figures 115, and the purpose of this second row of figures will presently appear. Slidably mounted in the block 110 is a pin 117 which normally engages in the recess between two threads of the worm 15 and is actuated by a spring-controlled lever 118 pivotally mounted on the handle 112. The pointer 111 cooperates with the scale-plate 114 and is designed to be set to various positions relative to said scale-plate to indicate the length of ribbon to be measured. In setting the pointer the lever 118 is pressed upward by the finger to draw the pin 117 out of engagement with the worm 15 and while held in such position the pointer 111 is moved, by sliding the block 110 over the rod 109, to a position opposite the figures on the scale-plate 114, or opposite one of the division marks thereon, to indicate and determine the length of ribbon which shall be drawn through the machine in the operation thereof. After the indicator has been set, the lever 118 is released and the pin 117 springs into engagement with the recess of the worm 115. The roller 7 is exactly $\frac{1}{4}$ of a yard in circumference, and the gearing is so proportioned that one revolution of the handle 20 will turn the roller 7 four times, the worm-shaft 15 two times, the winding-drum 86 four times, and advance the computing-drum 42 a distance corresponding to one-half a yard. The scale on the plate 114 is made by noting the position of the pointer 130

111 after each complete revolution of the handle 20, and dividing and sub-dividing the scale accordingly. From the above, therefore, it follows that with each complete revolution of the handle 20 the pointer 111 will be moved from zero to the mark indicating one-half a yard, and in two revolutions of the handle to the mark indicating a full yard, which will, of course, correspond to eight revolutions of the roller 7. It follows from the above, also, that the pin 117 will only enter between the threads on the worm 15 when the pointer 111 is directly opposite or over a division mark on the scale 114. Hence it is impossible for the operator to place the pointer between two division marks, and this prevents the necessity of the operator having to make a nice adjustment in setting the pointer. In practice the computing-drum and scale-plate would have divisions indicating eighths of a yard, but for clearness of illustration I have only shown sub-divisions of a quarter yard each. The superstructure 11 is provided in its top with a sight-opening 119, and mounted under this sight-opening and supported in the top of the superstructure is a magnifying glass 120 (Fig. 6). The outer end of the worm-shaft 15, at the termination of its screw-threaded portion, is provided with a stop 121 which is adapted to engage the pin 117, when the pointer 111 has been turned by the worm to the zero position, in order to positively stop the movement of the block 110 to prevent binding of the same against the casing by a continued turning of the shaft 20. Mounted on this same end of the worm-shaft 15 is a wheel 122 which is provided around its periphery with numbers running from "0" to "8" designating inches, and one revolution of said wheel, therefore, indicating nine inches or one-fourth of a yard. As thus far described, the operation is as follows:

45 It being desired to measure, say, nine and one-half yards of ribbon, the bolt of ribbon is placed in the recess 4, and the free end inserted in the recesses 12 and 58 between the rollers 7 and 8, the end of the ribbon 50 being moved to be flush, or substantially so, with the side of the superstructure 11. The push-button 63 is then depressed to release the rod 62 which thereupon is thrown upward by the spring 62 and the frame 48 thereby turned down to force the roller 8 against the ribbon and hold it in frictional contact with the roller 7. The operator then, in the manner described, sets the pointer 111 opposite the mark on the scale 114 indicated by "9 $\frac{1}{2}$ ". He then turns the handle and when a certain amount of ribbon has been drawn through the machine by the roller 7 he places the free end of the ribbon under one of the tongues of the winding-drum 86 and in the continued turning of the handle 20 the ribbon will be wound upon said winding-drum. As the operation continues the increase in bulk of the ribbon on the winding-drum will cause said ribbon to be drawn through the machine faster than it would be fed by the revolution of the roller 7. When this condition exists the winding-drum will slip on its shaft 89 and will thereby automatically adjust the pull of the ribbon on the winding-drum to the speed at which the ribbon is fed forward by the roller 7. By the continued rotation of the crank the pointer 111 will be continuously moved backward until it reaches the zero position when the pin 117 will engage the stop 121 and arrest further movement of the worm 15. During this movement of the handle, and through the gearing described, the computing-drum 42 will be turned to bring the numbers "9 $\frac{1}{2}$ " at each end to view through the sight-opening 104; and assuming that the price of the ribbon thus measured was nine cents per yard, the decimal number ".86" will appear directly below the number "9" of the series of figures 106, 90 showing the cost of the ribbon measured to be eighty-six cents. The thumb-piece 82 is now pressed down, and the shear 78 co-operating with the cutter 85 will operate to sever the ribbon. The operator then removes the ribbon wound upon the winding-drum 86 by a slight pressure upon the same to compress the tongues 99 and then sliding the ribbon off of the winding-drum. To enable the ribbon to be removed from between the rollers 7 and 8 the operator next presses downward the push-button 63 which operates to raise the frame 48 with its roller 8, and simultaneously, by engagement of the cam-surface 68 with the pin 66 move the gear 39 out of engagement with the gear 40, whereupon the spring 44 will return the computing-drum to the zero position, where it will be arrested by the engagement of the stop 47 with the arm 46.

55 In using the machine to ascertain the length of a piece of ribbon the pointer 111 is moved to the front end of the machine to lie opposite the mark indicated by "0" of the series of figures 116. The ribbon is then fed through the machine in the way previously described, and when the end of the ribbon is reached and has passed from between the rollers 7 and 8 the rotation of the handle 20 is stopped and the position of the pointer 111 with reference to the series of figures 116 will indicate the length in yards and fractions of a yard of the ribbon thus drawn through the machine. If the pointer has been moved to a position between two division marks of the scale the number on the wheel 122 will indicate the amount in inches over a quarter of a yard which has been drawn through the machine.

60 The part 2 of the frame extending be-

tween the recesses 4 and 5 is provided along either edge at its top with an apertured bead 123 (Fig. 4), in each of which is slidably mounted a rod 124, the outer ends of said rods being connected by a cross-bar 125 (Fig. 3). The rods 124 and cross-bar 125 form a frame, and by taking hold of the cross-bar said frame may be drawn outward and an extended support be thereby provided for accommodating ribbons of unusual width. When not required the frame is pushed back into inoperative position. A slide-plate 126 having curved outer edges for engaging the beads 123 forms a cover for the central portion 2^a of the casing, and when in inoperative position the cross-bar 125 lies flush with the outer edge of this plate, as indicated more clearly in Figs. 1 and 3, a central recess 127 being provided 20 in the end of the plate 126 to permit the operator to take hold of the cross-bar 125.

I claim:

1. In a machine of the class described, a frame providing an open-end recess for accommodating the bolt of ribbon from which the ribbon to be measured is to be unwound, and a supplemental support for the ribbon slidably mounted in the frame adjacent to said recess and movable in the direction of the length, and beyond the open end thereof.

2. In a machine of the class described, a frame providing on its upper side parallel circular recesses, respectively located at opposite sides of the machine, one of which recesses serves to accommodate the bolt of ribbon from which the ribbon to be measured is adapted to be unwound, a winding-drum located in the other recess, and ribbon feeding mechanism interposed between the two recesses.

3. In a machine of the class described, a frame providing on its upper side parallel circular recesses, respectively located at opposite sides of the machine, one of which recesses serves to accommodate the bolt of ribbon from which the ribbon to be measured is adapted to be unwound, a winding-drum located in the other recess, ribbon feeding mechanism interposed between the two recesses, and a cutter interposed between the feeding mechanism and the winding-drum.

4. In a machine of the class described, in combination with a feed-roll, a friction-roll movable into and out of engagement therewith, a rotatable, spring-controlled computing-drum, gearing operatively connecting said feed-roll and computing-drum, one element of said gearing being movably associated with the computing-drum, a handle for actuating said gearing to simultaneously rotate said feed-roll and computing-drum, the latter against the resistance of its spring, and means for raising said friction-roll and simultaneously releasing said movable gear-

element from engagement with said computing-drum to permit the spring controlling the latter to return it to the zero position, and a stop for arresting said computing-drum in the latter position.

5. In a machine of the class described, in combination with a ribbon-feed roll, a worm-shaft, an indicator slidably mounted adjacent to and movable by said worm-shaft, a scale operatively associated with said indicator, a winding-drum, gearing operatively connecting said worm-shaft, winding drum and roll, means for positively actuating said gearing, said gearing being proportioned to rotate said worm-shaft at a fixed ratio to the feed-roll, and said indicator being movable in the rotation of said worm-shaft to indicate on the scale the length of ribbon fed by the feed-roll, and a wheel on said worm-shaft having numbered divisions thereon corresponding in number to the number of inches measured by the circumference of the feed-roll.

6. In a machine of the class described, in combination with a feed-roll, a worm-shaft, an indicator slidably mounted adjacent to and movable by said worm-shaft, a scale operatively associated with said indicator, a computing-drum having sub-divisions thereon corresponding to those on said scale, and provided with a series of numbers after each subdivision indicating the cost of the number of yards represented by each subdivision at different prices per yard, a price-scale associated with said computing-drum, gearing operatively connecting said worm-shaft, feed-roll, and computing-drum, and proportioned to rotate said computing-drum in synchronism with the movement of said indicator, and means for placing said indicator in engagement with said worm-shaft and in line with any division mark on the scale indicating the length of ribbon to be measured, whereby, in the rotation of said gearing, the indicator will be returned to zero and the computing-drum will be turned to a position to indicate the number of yards of ribbon passed through the machine by said feed-roll.

7. In a machine of the class described, a feed-roll, a rotatable computing-drum having a gear, a friction-roll movable into and out of engagement with said feed-roll, gearing operatively connecting said feed-roll and computing-drum, one element of said gearing being movable into and out of mesh with the gear of said computing-drum, a handle for actuating said gearing to simultaneously rotate said feed-roll and computing-drum, a depressible member for raising said friction-roll out of contact with the feed-roll, means carried by said depressible member for simultaneously throwing said movable gear-element out of mesh with said computing-drum, and means to thereupon

automatically return said computing drum to zero.

8. In a machine of the class described, a feed-roll, a worm-shaft, an indicator adapted to be moved by said worm-shaft, a scale associated with said indicator and having division marks thereon indicating yards and fractions of a yard, a series of numbers on said scale-plate running in order from opposite ends thereof respectively, and designating yards, a wheel on said worm-shaft having divisions thereon corresponding in

number to the inches measured by the circumference of said feed-roll, gearing operatively connecting said feed-roll and 15 worm-shaft, and means for actuating said gearing.

In testimony whereof, I have hereunto set my hand in presence of two subscribing witnesses.

WALTER E. HOSCH.

Witnesses:

G. A. PENNINGTON,
STELLA HILL.
